UNITED STATES PATENT OFFICE.

EVERETT A. QUINT, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

SURGICAL NEEDLE AND METHOD OF MAKING IT.

Application filed March 18, 1926. Serial No. 95,637.

The object of my invention is to provide for the rapid production of surgical needles, of both the straight and curved type, by a method of manufacture which will insure 5 uniformity of product and which otherwise will obviate the objectionable features and disadvantages of the ordinary method of manufacture.

Heretofore, in the production of surgical 10 needles, the usual practice has been to soften the heel of the needle blank and to flatten the same with various forms of swaging dies in order to provide a member capable of being readily rolled to engage a ligature. 15 There are serious disadvantages coupled with this practice, to-wit,—inherent weakness at the juncture of the needle bar and the spread portion or heel, resulting in fatigue either immediate or eventual, and 20 hence, rendering the use of the needle hazardous; sometimes a well defined notch is formed at the juncture of the heel and body and usually there is not sufficient spread of metal to insure a closed seam or butt joint, 25 so that these conditions, the ragged edge of the notch and the spaced walls of the ligature engaging heel, tear and otherwise irritate the tissue; the security of the ligature is wholly dependent on the clenching action 30 of the rolled heel; and, finally, there is no assurance of uniformity of product in quantity production.

I depart from the old practice in a number 35 of respects and, generally stated, the nature of my invention consists in forming the spread portion or heel not alone from the needle bar but partly from the needle bar and partly from stock ultimately separated from the needle bar by the flanged 40 portion or heel. Otherwise stated, the heel is formed under conditions which insure uniformity of spread of metal and uniformity of metal section for the reason that the metal is not stolen from the needle body but 45 is contributed by the general stock. The actual method of its production is by pressing a groove radially of the stock to provide a longitudinally open tube or channel whereof the spaced walls are of sufficient 50 extent to insure flush contact when closed upon the ligature. By forming the flanges while their respective ends are supported by stock metal, I insure uniformity of metal section and avoidance of ragged edges. It 55 is also a merit of the invention that it does

not depend alone on the clenching action of the flanges for security of the ligature, but provides, in a simple way and incidental to the formation of the heel or flanged portion, an additional safeguard to prevent casual 60 separation of the ligature.

In the accompanying drawings, which illustrate the preferred embodiment of my inventive thought,—

Fig. 1 is a top view of the blank after 65 the initial steps of pointing, channeling, and tempering; following which the grooved or channeled portion is annealed or softened and the needle polished.

Fig. 2 is a section on line 2—2 of Fig. 1. 70

Fig. 3 is a side elevation.

Fig. 4 is a longitudinal sectional view of the channel showing the transversely ranging ribs for gripping the ligature.

Fig. 5 is a perspective view of the needle 75 structure after the removal of the dead end and the final shaping of the channel.

Fig. 6 shows the needle in its finished state with a ligature applied.

While the illustration is confined to a 80 straight needle, it is manifest that the method is applicable to curved types of needles and such is contemplated.

According to my invention, the blank or needle stock 5 is pointed as at 6 and its body 85 is longitudinally grooved by a pressing or extruding operation the effect of which is to displace metal laterally in one direction without disturbing the continuity of the bar to provide a longitudinally ranging channel 90 with walls 7 of uniform section the ends of which vanish in the stock. The article is then tempered. The next step is to anneal or soften the walls 7 to put them in condition for closing action upon the ligature. 95 The needle may then be polished or polishing may be resorted to after removing the dead end 8 and finally shaping the open tube or grooved portion. The channel generally is formed somewhat longer than required 100 to allow ample tolerance for finishing. As a result of the cropping or dead end removing operation, the extremity of the channeled heel is open its full section and readily admits of the introduction of the ligature 9. 105

The pressing down of the channel walls 7 establishes a closed seam or flush joint 10, Fig. 6, because the metal displacing operation can be so regulated as to spread the walls just enough to accomplish that result. 110

The effect of the channeling operation is of course to make for strength because the bottom 11 of the channel is uninterrupted bar stock; and the displacing operation is such 5 that the end wall 12 of the channel is not disposed at an abrupt angle but slopes gradually from the outside.

It is a merit of the invention that the tool for effecting the metal displacing or channeling operation may be of such nature as 10 to indent or upset metal within the channel area to provide a multiplicity of grips for the ligature. In the preferred embodiment the grips are in the form of transversely 15 ranging ribs 13 Fig. 4.

Having described my invention, I claim,—

1. A method for quantity production of surgical needles characterized by their uniformity and substantial freedom from fatigue, which consists in subjecting bar stock 20 to a metal displacing operation regulated as to depth so as to leave bridging bar stock free from mechanical strains and stresses while forming a groove which merges at 25 each end, without abruptness, in full section bar stock, dividing the stock transversely of

the groove area, tempering and pointing the divided stock, and annealing the burs formed by the displaced metal.

2. A method as in claim 1, wherein the groove is formed by piercing to a depth substantially half the thickness of the bar stock, and has a sloping end wall.

3. A method as in claim 1, wherein a groove with a ribbed surface is formed by 35 a piercing operation which leaves the major portion of the metal undisturbed, the side walls of the groove having an unbroken joint with the needle bar.

4. A surgical needle substantially free 40 from fatigue, consisting of full section bar stock having a groove pierced therein to about half depth, the groove having a sloping end wall and side walls which join the bar stock without a break and have burs 45 which are annealed whereby they may be availed of to close the groove, the bottom and sides of the groove being bar stock in its original form and devoid of stresses making for fatigue.

In testimony whereof I affix my signature.
EVERETT A. QUINT.
